(57) **CLAIM**

The ornamental design for a front face of a vehicle wheel, as shown and described.

DESCRIPTION

This application is related to the following co-pending application: Application Ser. No. 29/283,807, filed August 24, 2007, and entitled Front Face of a Vehicle Wheel.

FIG. 1 is a front view of a front face of a vehicle wheel according to our novel design; and,

FIG. 2 is a perspective view thereof.

The broken lines are for illustrative purposes only and form no part of the claimed design.
